UNITED STATES PATENT OFFICE.

CHARLES P. THORNTON AND WILLIAM H. MOODY, OF MAGNOLIA, ARKANSAS, ASSIGNORS TO SAID THORNTON, AND J. R. LE BOSQUET AND L. ROTH, OF PINE BLUFF, ARKANSAS.

WAGON-STEP.

SPECIFICATION forming part of Letters Patent No. 599,666, dated February 22, 1898.

Application filed March 10, 1897. Serial No. 626,826. (No model.)

To all whom it may concern:

Be it known that we, CHARLES P. THORNTON and WILLIAM H. MOODY, citizens of the United States, residing at Magnolia, in the county of Columbia and State of Arkansas, have invented a new and useful Wagon-Step, of which the following is a specification.

This invention relates to improvements in wagon-steps.

10 The object of the invention is to improve the construction of wagon-steps and to provide portable ones which will be adapted to be readily attached to the body or bed of a farm-wagon for enabling persons to enter and leave a wagon readily and which will be capable of folding compactly when not in use.

Another object of the invention is to provide wagon-steps which will be capable of ready adjustment to suit the height of a wagon-body and which will be adapted to be connected with either the ordinary wagon-bed or top box and which will be held firmly in position when subjected to the weight of a person.

25 The invention consists in the construction and novel combination and arrangement of parts, as hereinafter fully described, illustrated in the drawings, and pointed out in the claims hereto appended.

30 In the accompanying drawings, Figure 1 is a perspective view of portable wagon-steps constructed in accordance with this invention. Fig. 2 is a similar view, the steps being folded. Fig. 3 is a detail perspective view 35 of one of the cuffs.

Like numerals of reference designate corresponding parts in the several figures of the drawings.

1, 2, and 3 designate upper, lower, and intermediate sections, each composed of side bars and steps connecting the same. The sections are adapted when extended to rest upon the ground and against a side or end of a wagon bed or body, as illustrated in Fig. 1 of the accompanying drawings, and they are also adapted to be folded compactly, as illustrated in Fig. 2. The upper section, which is provided near its top with a cross-piece or rung 4, has hooks 5 at the upper ends of its 45 sides for engaging over the upper edges of a wagon-body, and the said upper section, which

is adapted to fit against a wagon-body, is arranged vertically when in operative position and braces the wagon-bed from the top to the bottom and is provided near its bottom with 55 a step 6.

The sides of the upper section are provided at their lower ends with metal straps or cuffs 7, projecting forward horizontally beyond the sides of the upper section and perforated to 60 form ears for the reception of pivots 8, which connect the upper terminals of the sides of the intermediate section 3 to the upper section. The straps or cuffs 7, which are substantially rectangular, are arranged on the 65 inner and outer faces of the sides of the upper section and extend around the inner or rear edges of the same, and the upper terminals of the sides of the intermediate section bear against the front edges of the sides of 70 the upper section and are rounded to permit the intermediate section to swing upward readily for folding and to prevent binding.

The intermediate section, which has the upper and lower steps 9, is provided near its 75 bottom with metal straps or cuffs 10, projecting rearward from the sides of the intermediate section and perforated to form ears for the reception of pivots 11 of the lower section. The lower section 2, which is provided with 80 a step 12, is inclined, as shown in Fig. 1, when in operative position and abuts against the rear edges of the lower ends of the sides of the intermediate section, bracing the same and holding the intermediate section perfectly 85 rigid. The upper ends of the sides of the lower section are rounded, and the latter is adapted to fold backward against the intermediate section, as clearly shown in Fig. 2.

When the wagon-steps are in operative position, as illustrated in Fig. 1 of the accompanying drawings, the upper section, which rests against the wagon body or box, is arranged vertically and the lower and intermediate sections extend outward at an inclination. The steps are adjustable to suit the height of a wagon-body by varying the angle formed by the upper section and the lower and intermediate sections, and when the steps are subjected to the weight of a person they 95 are firmly held in operative position and in engagement with the wagon-body.

The steps may be arranged either inside a wagon or on the ground to support the end-gate for forming a seat, and when used for this purpose the sections are arranged at an angle to one another or disposed zigzagly, with one side bar of each section resting upon the bottom of the wagon-body or upon the ground, so that the other side bars will lie in a horizontal plane to receive the end-gate.

10. It will be clear that the following advantages result from the folding steps: The top section by resting vertically against the wagon-body or box and engaging the upper edges of the same braces the said body or box from the top to the bottom. The steps are readily adjustable to wagon-bodies of different heights by varying the angle formed by the upper section and the lower and intermediate sections, and the strain to which the steps are subjected operates to hold them firmly in position and in engagement with the wagon-body. They also possess lightness, strength, and durability and operate perfectly, and when not in use fold compactly and occupy but a small amount of space.

What we claim is—

1. Portable wagon-steps comprising an upper section provided at the upper edges of its sides with devices for engaging the upper edges of a wagon-body, perforated ears projecting forward from the lower ends of the sides of the upper section, the intermediate section having its sides pivoted to the perforated ears and adapted to swing upward against the front edges of the sides of the upper section, perforated ears projecting rearward from the sides of the intermediate section and located a short distance above the lower ends thereof, and the lower section having its sides pivoted to the perforated ears of the intermediate section and arranged to abut against the rear edges of the sides of the same, said lower section being adapted to fold against the intermediate section, substantially as described.
2. Portable wagon-steps comprising an upper section provided with devices for engaging a wagon-body, perforated ears projecting from the lower end to which an intermediate section is pivoted, perforated ears projecting rearward from lower end of intermediate section, and a lower section pivoted to the perforated ears of the intermediate section, said upper and lower sections adapted to fold against the intermediate section, substantially as described.

35. 35. 40. 45. 50. 55.

In testimony that we claim the foregoing as our own we have hereto affixed our signatures in the presence of two witnesses.

CHAS. P. THORNTON.
WM. H. MOODY.
